COMBINED VALVE LIFTER AND SPRING COMPRESSOR

Joseph Sunnen, Kirkwood, Mo.

Application May 15, 1933, Serial No. 671,087

4 Claims. (Cl. 29—86.3)

My invention has relation to combined valve lifters and spring compressors for use in performing service operations on automobile engines, and it consists in the novel features of construction 5 more fully set forth in the specification and pointed out in the claims.

The invention is more particularly directed to what may be termed the overhead type of spring compressor in that it has its support on top of the 10 motor block while compressing the spring preparatory to removing a valve. Because of the manner in which this type of valve lifter is operated the frame is necessarily formed in the shape of a loop, or C, and is also referred to among mechanics as a C-type lifter.

Because of the wide span between the point of support and the movable seat for compressing the spring this type of lifter heretofore has not been very successful on account of the difficulties of 20 making the frame sufficiently strong without undue cumbrousness and excessive weight. It is the principal object of the present invention to so construct the lifter frame that it will combine strength and rigidity with light weight, and at the 25 same time so arrange the operating parts that the lifter may be actuated with convenience and minimum effort.

It is a further object of the invention to embody 30 into the tool spring compressor mechanism which shall be actuated by the same operating parts that actuate the valve lifter, and to so arrange the spring compressor that it too may be conveniently operated. In a valve lifter of this type, which is inherently bulky, the arrangement 35 of the parts with a view to convenience and simplicity of operation is of the utmost importance in order that the tool may be practical. It is also an object of the invention to provide means for securely holding the spring while compressing 40 the same, said means readily accommodating itself to springs of various sizes within a given range. Further and other advantages will be better apparent from a detailed description of the invention in connection with the accompanying 45 drawings, in which:

Figure 1 is a side elevation of my improved valve lifter and spring compressor shown applied to a motor block, which is shown in partial section; Fig. 2 is a top plan of my invention; Fig. 3 50 is a side elevation of my invention shown applied to a spring for compressing the same, the lower part of the frame being broken away; Fig. 4 is a front elevation of the invention; and Figs. 5 and 6 are detailed plan views on an enlarged scale 55 showing how the spring holder accommodates different sizes of springs preparatory to compressing them.

Referring to the drawings, M represents a motor block, the valve V of which is to be removed. 60 As is well known in the art, the valve V cannot

be removed without first disconnecting the valve spring S from the valve stem V', said spring being seated in the valve seat or washer S' held securely to the valve stem V' by the lock L. The function of the valve lifter is to raise the spring sufficiently so that the lock L may be removed and thereby disengage the valve from the spring S whereupon the valve is readily lifted out of place. My improved valve lifter comprises a frame 1, shaped in the form of the letter C, said frame having a cross-section of a hollow rectangle. The specific construction of the frame and the method of obtaining the frame in the shape of a hollow rectangle is novel as far as I am aware but is not claimed in this application as it is made the subject of a separate application for a patent filed of even date herewith. The lower end of the frame 1 carries in permanently fixed relation a channel-shaped extremity 2 bifurcated at its outer end so as to provide flanged seats 3, 3 for the spring S to which the valve lifter is applied. Openings o, o are provided in the top and bottom walls of the upper horizontal part 1' of the frame 1 and a tubular bearing 4 is securely fixed into said openings, said bearing 80 being of substantial length and having its longitudinal axis coincident with the center point between the seats 3, 3 so that when the valve lifter is applied to the spring S and the frame, held so that the upper portion 1' is in a horizontal position, the tubular bearing 4 will be directly in line with the valve V. The importance of the alinement of these parts will be apparent 85 from what follows.

A square threaded screw 5 is slidably mounted 90 in the bearing 4 and has a handle 6 fixed to its upper end, said handle comprising spaced cross-members 7, 7 secured together at their outer ends by suitable connectors 8, 8. The screw 5 carries a block 9 on its threaded portion, said block being internally threaded to fit the threads of the screw 5, whereby the position of the block on the screw may be adjusted by rotating the screw in its bearing sleeve 4 so that it may be either advanced through or withdrawn from the block 95.

An operating lever 10 is pivotally connected 100 on the side of the frame 1 near the juncture of the horizontal portion 1', said lever having a lug 11 projecting laterally from it through which it is mounted on a stud 12 projecting outwardly 110 from one side of said frame. The lever 10 is held in spaced relation with the side of the frame 1 by means of suitable spacing washers 13, 13 and is confined on the stud 12 by a nut 14. A pair of toggle links 15 and 16 are connected between the block 9 and the horizontal portion 1' of the frame 1, the upper link 15 having a lug 17 projecting from it in close proximity with the rivet 18 which connects the links 15 and 16 together. A connecting link 19 has one end piv- 115

totally connected to lug 17 and the other end pivotally connected to the short lever arm 20 of the lever 10 so that on actuating the lever 10 the link 19 will transmit the lever movement 5 to the toggle and raise and lower the block 9 to which the toggle link 16 is pivotally connected at 21. It will be observed by referring to the dotted position in Fig. 1 that the block 9 and, of course, the screw 5 are in their elevated positions when the actuating lever 10 is elevated, and that as said lever is pulled downwardly, the screw 5 is also moved downwardly (or if the screw 5 is held in place the entire frame will be moved upwardly). When the handle 10 of the 10 lever 10 is in its lowermost position it lies almost entirely within the margins of the frame 1 and the toggle links 15 and 16 are slightly beyond dead center so that no amount of pressure upwardly on the screw 5 can dislodge it. The ultimate downward movement of the lever 10 is obtained when the connecting link 19 comes into abutting relation with edge 11' of the lug 11 (as shown dotted in Fig. 1).

From the foregoing it should be apparent that 25 the arrangement of the actuating parts, including the position of the handle 10' of lever 10, when said lever has been moved to its full extent downwardly, greatly facilitates the operation of the tool by the mechanic. For instance, he 30 may hold the frame 1 with his right hand, including in his grip the handle 10', while his left hand is free to remove the lock L which releases the valve V so that it may be lifted out of the block. It should also be apparent that when the 35 lever 10 approaches its lowermost position, the stresses on the tool are greatest and the force applied to the handle comes almost directly opposite the lower end of screw 5 (the point of anchorage), reducing to a minimum any torsional strains on the frame 1.

As heretofore stated, my improved valve lifter also embodies a spring compressor, which includes the same parts that serve as the operating mechanism for the valve lifter. At the front of 45 the horizontal component 1' of the frame 1 is a bracket 22, the upper surface 23 of which lies in a plane about midway between the top and bottom walls of the component 1' and a rectangular post 24 projects upwardly from the surface 23 in 50 spaced relation with the forward end 25 of component 1'. The bracket 22 serves as a support for the spring S that is to be compressed, the spring being confined in the space between the post 24 and the forward end 25 of frame component 1'. 55 By referring to Figs. 5 and 6 it will be seen that the dimensions of the post 24 and the spacing of the post from the end 25 are such that whether a large or small spring is to be compressed the spring is closely confined between three points, i.e., edges e, e of the post and the surface 25 of 60 the frame. It is possible to fix these dimensions so that the confinement of any size spring will be secure because in the smaller sized springs the shorter radius fills up the space between the post and frame, while in the larger sized springs the greater thickness of the spring coils serves to fill the space. After the operator has passed the spring S over the post 24 he adjusts the position of the screw 5 so that the cross-arms will engage 65 the spring when the handle 10 is raised whereupon the movement of the handle downwardly forces the spring coils together (Fig. 3). The tool may 70 now be held in the right hand which, as above

explained, can grip the handle 10' together with the frame 1 and suitable clips C may be placed on the spring with the left hand to hold it in its compressed state so that it may be removed from the tool and subsequently put in place in the 80 valve assembly.

Having described my invention, I claim:

1. In a combined valve lifter and spring compressor, a handle frame, a socket disposed transversely at one end of said frame, a member slidably mounted in said socket for coaction with the frame, a block adjustably mounted on said member, spring retaining means on the end of the frame beyond and adjacent to said socket, a cross-arm on one end of the sliding member, and means connected between the said block and frame for moving the sliding member back and forth through the socket, said spring retaining means comprising a seating surface and confining elements perpendicular to said surface and arranged to contact the spring coils at three points. 90

2. In a combined valve lifter and spring compressor, a handle frame, a socket disposed transversely at one end of said frame, a member slidably mounted in said socket for coaction with the frame, a block adjustably mounted on said member, and a series of actuating levers pivotally mounted on said frame at the side thereof, said actuating levers comprising a toggle connected to the frame at one end and to the block at the other, a handle lever having a fulcrum connected to the frame at a point horizontally spaced from the socket end thereof, and a link connected at one end to the inner end of the handle lever in close proximity to said fulcrum, said link being connected at the other end near the joint of the toggle. 100

3. In a combined valve lifter and spring compressor, a handle frame, a socket disposed transversely at one end of said frame, a member slidably mounted in said socket for coaction with the frame, a block adjustably mounted on said member, and a series of actuating levers pivotally mounted on said frame at the side thereof, said actuating levers comprising a toggle connected to the frame at one end and to the block at the other, a handle lever having a fulcrum connected to the frame at a point horizontally spaced from the socket end thereof, a link connected at one end to the inner end of the handle lever in close proximity to said fulcrum, said link being connected at the other end near the joint of the toggle, and the fulcrum and the link connection with the handle being in line with the 110 joint when the handle is raised. 120

4. In a combined valve lifter and spring compressor, a handle frame, a socket disposed transversely at one end of said frame, a member slidably mounted in said socket for coaction with the frame, a block adjustably mounted on said member, spring retaining means on the end of the frame beyond and adjacent to said socket, a cross-arm on one end of the sliding member, and means connected between the said block and frame for moving the sliding member back and forth through the socket, said spring retaining means comprising a seating surface and confining elements perpendicular to said surface and spaced to contact the coils of varying sizes of 130 springs at three points. 140

JOSEPH SUNNEN.
